UNITED STATES PATENT OFFICE.

JAY H. HALL, OF CLEVELAND, OHIO, ASSIGNOR TO THE ELECTRIC CONTROLLER AND MANUFACTURING COMPANY, OF CLEVELAND, OHIO, A CORPORATION OF OHIO.

ELECTRIC CONTROLLER.

1,053,502.

Specification of Letters Patent.

Patented Feb. 18, 1913.

Application filed June 7, 1911, Serial No. 631,760. Renewed October 25, 1912. Serial No. 727,784.

To all whom it may concern:

Be it known that I, JAY H. HALL, a citizen of the United States, residing at Cleveland, in the county of Cuyahoga and State 5 of Ohio, have invented new and useful Improvements in Electric Controllers, of which the following is a specification.

My invention relates to electric motor controllers of that type in which separately 10 actuated magnetic switches are used to make the proper connections for starting the motor, operate it in different directions, and vary its speed. It sometimes occurs in the 15 operation of such controllers that, when the master controller is moved to the off position, some one of the resistance cutout switches may remain closed due to a heavy arc which has been formed at its contacts which welds them together.

20 The object of my invention is to provide a controller in which it will be impossible to operate the main switch or reverser in case any of the resistance cutout switches is closed. This may be accomplished in a 25 number of ways as illustrated in Figures 1 to 5 of the accompanying drawings, which show diagrammatically five species of my invention.

In Fig. 1, S⁴ and S⁵ are reversing switches, 30 and S', S², S³ are resistance switches arranged to control a motor having the armature A and the series field F. The switches S', S², S³, which short-circuit the sections of the starting resistance R', R², R³, are 35 series switches, having their operating coils c', c², c³ connected in the motor circuit, and are of the type described in Canfield's application, Serial Number 583,000. A master controller is shown at M for operating the 40 motor in either direction. The operating coils c', c⁵ on the reverse switches have one end connected to contacts n', m' on the master switch; the other end of said coils is connected to the positive side of a line 45 switch S. When the coil c⁴ or c⁵ is energized it closes its respective switch, the contact m on the master switch being connected directly to the negative. At u and d are 50 shown locking-out coils which, when energized, prevent the operating coil c⁴ or c⁵ from closing its respective switch, but which, after the switch is closed, do not cause it to open. The locking-out coils are connected in series in a circuit leading from a 55 point such as a on the positive main through

the coils u and d, resistances r, r', r², and to the movable member of the switches S', S², S³, the resistance r' being connected between the switches S' and S², and the resistance r² being connected between the 60 switches S² and S³.

The movable member of each resistance switch carries a bridging piece, which is adapted to connect the fixed contacts thereof.

If all of the switches are open, as shown in 65 Fig. 1, and the master controller is moved to the first position on either side of the center, the corresponding operating coil of the reverser becomes energized. Current flows from the positive side of the switch S through the coil c⁴ or c⁵ and to the negative at the master controller M, and the reversing switch whose coil is energized closes, there being as yet no current in the locking-out 70 circuit to prevent its operation. As soon as 75 the selected reversing switch closes, the motor-circuit is completed from the positive side of the switch S through the armature A of the motor, the field F, the starting resistance R³, R², R', and the coil c' of the 80 switch S', to the negative side of the switch S. For the switches S', S², S³, I prefer to use the type shown in Canfield's applications, Serial Number 583,000, filed September 21, 1910, and Serial Number 604,331, 85 filed January 23, 1911, and in Eastwood's Patent, No. 1,040,292, granted October 8, 1912. In these applications and in this patent, particularly in Fig. 2, the series switch locks itself open automatically so 90 long as the current in the motor circuit is above a predetermined limit. When the current falls below that limit, the switch closes automatically. Consequently, when the first rush of current has subsided, the 95 resistance switch S' closes, thereby short-circuiting the first section R' of the resistance and completing the locking-out circuit of the reverser through the movable member of the switch S', and the coil c' of the said 100 switch to the negative. The reversing switch not operated is, therefore, locked in the open position. The operation of the switch S' short-circuits the section R' of the resistance and connects the actuating coil c² 105 of the switch S² in circuit. The switch S² then operates, short-circuiting the resistance R²; and, finally, the switch S³, in operating, short-circuits the last resistance R³, as is 110 fully described in Canfield's said applica-

tion. The resistance r in the locking-out circuit is for the purpose of limiting the amount of current in the coils u and d and decreasing the heating of the said coils. The resistances r' and r^2 have a different function, namely, to avoid short-circuiting the actuating coils c^2 and c^3 of the switches S^2 and S^3 when these switches close. Were it not for the resistance r' , for instance, the 5 operation of the switch S^2 would close a short-circuit around the coil c^2 from the contacts of the switch S^2 through the movable member of this switch, the movable member of the switch S' , and its contacts. This 10 short-circuit would deenergize the coil c^2 and start a pumping action of the switch S^2 . Likewise the resistance r^2 prevents the establishment of a short-circuit around the coil c^3 when the switch S^3 operates. It is 15 possible so to connect the main contacts to these switches that the main contacts of one switch are connected to the main contacts of the adjacent switch, which arrangement does not require the presence of the resistances 20 r' — r^2 , as may be seen by referring to Fig. 5. When the master controller M is returned to the center, all the switches S' , S^2 , S^3 should 25 drop to the open position. If one of them, say S^2 , stays closed, it is impossible to start 30 the motor again in the same direction or to reverse it because current flows in the locking-out circuit from the positive through the coils u and d , the resistance r , the resistance r' , the switch S^2 , the resistance R' , and 35 the coil c' of the switch S' to the negative, thereby energizing the coils u and d which prevent the operation of switch S^4 or S^5 and protect the motor A from possible injury.

In Fig. 2, the resistance switches S' , S^2 , 40 S^3 are of the same type as those shown in Fig. 1. The interlocking feature of the reversing switches S^4 and S^5 is accomplished by means of an interlocking relay S^6 controlling the contacts K^3 in the actuating circuit of the coils c^4 and c^5 . The reversing switches are provided with the auxiliary contacts K' and K^2 , the function of which is to provide a maintaining circuit for the reversing switch operated, independent of the 45 interlock relay S^6 . A resistance r^5 is inserted in said maintaining circuit. The interlocking relay circuit is traced from the positive through the coil c^6 , and the resistance r , and then is connected to each of the 50 movable members of the switches S' , S^2 , S^3 , any one of which completes the circuit to the negative whenever it closes.

Assuming that all the resistance switches are open, the interlocking relay S^6 is down, 55 and the master controller M is on contact m' or n' , an actuating circuit is closed from the positive main through the contacts K^3 on the relay S^6 , and the coil c^4 or c^5 to the negative through the master controller M . The switch S^4 or S^5 closes, establishing its

own maintaining circuit from the positive through the resistance r^5 , the contacts K' or K^2 , and the coil c^4 or c^5 to the negative through the master controller. At the same time current flows in the motor circuit from 70 the positive through the reversing switch operated, the armature A , the field F , the resistances R^3 , R^2 , R' , and the operating coil c' of the switch S' , to the negative. When the switch S' closes, the circuit of the 75 relay S^6 is completed from the positive through the coil c^6 , the resistance r , the switch S' , and the coil c' to the negative. The coil c^6 being energized operates the relay S^6 , thereby opening at the contacts K^3 80 the actuating circuit of the reversing switches. The switches S^2 , S^3 , will close in order, short-circuiting the remaining sections of starting resistance, as explained when describing Fig. 1. All the resistance 85 switches should drop to the open position when the master switch is brought back to the center position. However, if from any cause one of them, say S^2 , stays closed, the interlocking relay circuit is closed, current 90 flowing from the positive through the coil c^6 , the resistance r , the resistance r' , the switch S^2 , the resistance R' and the coil c' to the negative. It follows that the relay S^6 is operated and the contacts K^3 are open. 95 Therefore, it will be impossible to energize either actuating coil c^4 or c^5 of the reversing switches and, consequently, to start again the motor in the same direction or to reverse it by manipulation of the master controller. 100

In Fig. 2, the resistance r is for limiting the amount of current in the coil c^6 , and the function of the resistances r' and r^2 , is to prevent the establishment of a short-circuit 105 around the coils c^2 and c^3 when the switches S^2 and S^3 operate.

Fig. 3 shows a system of electric motor control in which the interlock for preventing the reverser or main switches from operating when any of the resistance 110 switches is closed is provided by a pair of resistances r^3 , r^4 , associated with the common junction of the reverser operating coils. The resistances r^3 , r^4 , are connected in series, one end of the circuit being joined to the positive and the other end being connected to the movable members of the resistance cut-out switches S^6 , S^7 , S^8 . These resistance switches are actuated by the shunt coils c^6 , c^7 , c^8 , one end of each of 115 which is permanently connected to the positive through a common wire, and the other end is connected to the negative by the operation of the master controller M' . 120

If the master controller is moved to the 125 first position on either side of the center or off-position, one of the operating coils c^4 , c^5 of the reverser will receive current from the positive through the resistance r^3 , the coil c^4 or c^5 , and the master controller to the nega- 130

tive. This will allow sufficient current to pass through the operating coil to close the respective reversing switch whereupon the motor circuit is established, from positive 5 through the reversing switch operated, the armature A, the field F, and the resistances R³, R², R'. This operation will be allowed to proceed provided none of the resistance switches S⁶ to S⁸ is closed. If, however, one 10 of them, say S⁷, is closed, a circuit will also be established from the positive through the resistance r³, the resistance r⁴, and the switch S⁷ to the negative. It will be seen that the operating coil of the reverser which 15 is energized is now connected in parallel with the resistance r⁴, the two parallel circuits being in series with the resistance r³. Since the total amount of current through this two-branch circuit is limited by the resistance r³, the amount of current in the operating 20 coil of the reverser is smaller, and the resistances r³ and r⁴ may be so proportioned that, when this circuit through r⁴ is established, the current in the operating 25 coil will not be sufficient to close the reverser. Sufficient current must flow, however, through the operating coil to hold the reverser closed after it has once operated, since, in the normal operation of the controller after the reversing switch has operated and resistance switch S⁶ is closed, this circuit through the resistance r⁴ will be established. This arrangement, in addition to securing the electrical interlock, has also 30 the advantage of reducing the amount of current in the operating coil of the reverser after the closure of the first resistance switch, which is desirable to prevent overheating of the coil.

Fig. 4 shows another form of my invention in which the reversing switches are provided with auxiliary contacts which are closed when the reversing switches are open. One end of the coils c⁴ and c⁵ is joined to 40 a wire which on one side is connected to the movable member of the switches S⁶, S⁷, S⁸ and on the other is connected to the positive through a resistance r⁶. In the normal operation of the controller, when all the resistance switches S⁶ to S⁸ are open at start, and the master controller is moved to the first position, one of the operating coils c⁴ or c⁵ is connected in a circuit from the positive through resistance r⁶, the coil c⁴ or c⁵, and the master controller M' to the negative. The resistance r⁶ allows sufficient current to flow to operate the switch. This operation causes the auxiliary contact to open on this switch, which cuts off the connection to the switches S⁶, S⁷, S⁸, preventing current from flowing through this branch of the circuit when any or all of said switches are closed. If, however, any of the resistance switches 55 should remain closed from a previous operation, the negative will be connected through

this closed switch and the auxiliary contacts of the reverser to the lower end of the reverser coils. When the master controller is moved to the first position, the negative is connected through the master controller to the upper end of the coil of the reversing switch which it is desired to close, but no current will flow through this coil and it will be, therefore, impossible to operate the corresponding switch.

In Fig. 5, the part of the diagram not shown is intended to be the same as in Fig. 1. Upon closure of one of the reversing switches, current flows through the motor circuit to the point at the left of the resistance R², thence through the resistances R² and R', the winding c' on the switch S', and the resistance R³ to the negative. Upon the closure of the switch S', current flows through the resistance R², the contacts of the switch S', the winding c², the winding c', and the resistance R³ to the negative, thus short-circuiting the resistance R'. Upon the closure of the switch S², the current flows through the winding c³, the contacts of the switches S² and S', the windings c² and c', and the resistance R³ to the negative, thus short-circuiting the resistance R². Upon the closure of the switch S³, current flows through the winding c³, and the contacts of the switch S³ to the negative, thereby short-circuiting the windings c² and c' and the resistance R³. Since the windings c² and c' are now deenergized, the switches S² and S' fall to their opening position. Since the main contacts of the switches S', S², S³, are all directly connected to each other by the main motor connections, there will be no tendency for the main current to pass from one pair of switch contacts to another through the locking-out circuit, because the resistance of the locking-out circuit would be somewhat greater than that of the main circuit due to the smaller size of the conductor. For this reason it is not necessary to use the resistances r'—r² in the locking-out circuit between adjacent switches when the main circuit contacts are arranged as shown in Fig. 5.

In each form of my invention, the motor circuit is established, that is, completed as soon as a reversing switch operates, thereby dispensing with a circuit-closing or main switch, and the electrical interlocking is secured after the operation of the first resistance switch. In Figs. 1 and 3, the interlock is also obtained without the use of auxiliary contacts. These interlocking devices may be applied also to motor starters having no reversing switches, the locking-out devices described preventing the operation of the main switch, when any resistance switch is closed. I have shown the interlocking circuit connected to each of the resistance switches but it may be connected to one or more of them, if desired, whereby the lock-

ing system will protect the reversing switches from closing only when those which are connected to the locking circuit remain closed on the opening of the master switch.

5 I claim—

1. In a system of motor control, the combination with a motor, a circuit therefor, a starting resistance, a series of resistance switches, a master controller, a switch for establishing a flow of current in said circuit, and an operating circuit therefor closed by the master controller, a locking-out circuit one end of which is connected to the same side of the source of supply as the said switch, and the other end of which is connected to the movable member of one or more of the resistance switches.
2. In a system of motor control, the combination of a motor, a circuit therefor, a starting resistance, a series of resistance switches having contacts in said circuit, a master controller, a switch for establishing a flow of current in said circuit, means for operating the switch, and means including the said contacts for preventing the operation of the switch when any of the resistance switches is closed.
3. In a current-varying controller, a series of resistance switches each having a pair of contacts and a bridging piece, a switch, means for operating the switch, and a locking-out coil therefor connected in a circuit one end of which is connected to a source of supply, the other end being connected to the bridging piece of one or more of the resistance switches.

4. In a current-varying controller, a series of resistance switches, a switch, means for operating the switch, a locking-out coil therefor connected in a circuit one end of which is connected to a source of supply, the other end being connected to the movable member of one or more of the resistance switches, and a resistance in the locking-out circuit between two consecutive resistance switches.

5. In a current-varying controller, a circuit, one or more resistance sections therein, switch contacts for controlling the sections in said circuit, a switch for establishing current flow through said circuit, and means including said switch contacts for preventing the closure of the switch when any of said switch contacts is closed.

6. In a motor control system, a motor, a circuit therefor, a series of switch contacts for controlling the motor, a switch for establishing current flow through said circuit, and means including the said switch contacts for preventing the said switch from operating when any of the switch contacts is closed.

7. In a current-varying controller, a circuit, a resistance therefor, a switch for controlling the resistance, having a contact-closing bridging-piece, a switch for connecting said circuit to a source of supply, and means connected to the bridging-piece for preventing the circuit-connecting switch from closing when the bridging-piece closes on its contacts. 65

8. In a current-varying controller, a circuit, a resistance therefor, a pair of contacts connected to the resistance, a bridging-piece for the contacts, a switch for connecting the circuit to a source of supply, and a locking circuit for preventing the operation of the switch, the locking circuit being connected to the bridging-piece and energized when the bridging-piece connects with one of the said contacts. 70

9. In an electric controller, a circuit, a pair of contacts in the circuit, a bridging-piece for the contacts, a switch, and means for preventing the operation of the switch including a locking circuit connected to the bridging-piece and energized when the bridging-piece connects with one of the said contacts. 80

10. In an electric controller, a circuit to be controlled, a switch for establishing a flow of current in the circuit, a second switch having contacts for controlling the circuit, and means including the contacts of the second switch for preventing the closure of the first switch when the second switch is closed. 90

11. In an electric controller, a motor, a circuit therefor, a resistance in the circuit, a switch for establishing a flow of current in said circuit, a second switch having contacts in the circuit for controlling the resistance, an operating winding for the second switch energized by the current in the circuit, and means including the contacts of the second switch for preventing the closure of the first switch when the said contacts are closed. 100

12. In an electric controller, a motor, a circuit therefor, a resistance in the circuit, a switch for establishing a flow of current in the circuit, a second switch having contacts in the circuit for controlling the resistance, and a locking magnet energized by current through the said contacts for preventing the operation of the first switch when the said contacts are closed. 110
